UNITED STATES PATENT OFFICE

147,619

DESIGN FOR A LIPSTICK HOLDER

Richard C. Jones, Chicago, Ill., assignor to Associated Products, Inc., Chicago, Ill., a corporation of Illinois

Application April 4, 1946, Serial No. 128,283

Term of patent 7 years

(Cl. D86—10)

To all whom it may concern:

Be it known that I, Richard C. Jones, a citizen of the United States, residing at Chicago, in the county of Cook and State of Illinois, have invented a new, original, and ornamental Design for a Lipstick Holder, of which the following is a specification, reference being had to the accompanying drawing, forming part thereof.

Fig. 1 is a front elevational view of a lipstick holder, showing my new design.

Fig. 2 is a plan view thereof.

The design of the side of my lipstick holder not shown is the same as the side disclosed in Fig. 1 of the drawing.

The essential features of my design reside in the portions shown in full lines.

I claim:

The ornamental design for a lipstick holder, substantially as shown and described.

RICHARD C. JONES.
